DESIGN FOR A KNIFE HOLDER

Fred H. Lewis, Evanston, Ill.

Application March 29, 1944, Serial No. 113,064

Term of patent 14 years

(Cl. D44—29)

To all whom it may concern:

Be it known that I, Fred H. Lewis, a citizen of the United States, residing at Evanston, in the county of Cook and State of Illinois, have invented a new, original, and ornamental Design for Knife Holders, of which the following is a specification, reference being had to the accompanying drawing, forming part thereof.

In the drawing: Figure 1 is a perspective view of a knife holder, showing my new design; Figure 2 is a top plan view; and Figure 3 is an end elevational view of the same.

I claim:

The ornamental design for a knife holder, substantially as shown.

FRED H. LEWIS.
